(57) **CLAIM**

The ornamental design for wireless earbuds, as shown and described.

DESCRIPTION

FIG. 1 is an isometric view of wireless earbuds showing the new design;

FIG. 2 is a front view of the right earbud of the wireless earbuds shown in FIG. 1;

FIG. 3 is a top view of the right earbud shown in FIG. 2;

FIG. 4 is a left side view of the right earbud shown in FIG. 2;

FIG. 5 is a rear view of the right earbud shown in FIG. 2;

FIG. 6 is a right side view of the right earbud shown in FIG. 2;

FIG. 7 is a bottom view of the right earbud shown in FIG. 2;

FIG. 8 is a front view of the left earbud of the wireless earbuds shown in FIG. 1;

FIG. 9 is a top view of the left earbud shown in FIG. 8;

FIG. 10 is a right side view of the left earbud shown in FIG. 8;

FIG. 11 is a rear view of the left earbud shown in FIG. 8;

FIG. 12 is a left side view of the left earbud shown in FIG. 8;

FIG. 13 is a bottom view of the left earbud shown in FIG. 8; and,

FIG. 14 is an isometric view of the wireless earbuds of FIG. 1 shown inserted into a protective case.

The broken lines in the drawings depict portions of the wireless earbuds that form no part of the claimed design. The broken line showing the protective case in FIG. 14 depicts environment and forms no part of the claimed design.

1 Claim, 8 Drawing Sheets
